UNITED STATES PATENT OFFICE.

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY.

SOLE-CHANNELING MACHINE.

1,383,448.

Specification of Letters Patent. Patented July 5, 1921.

Application filed June 7, 1919. Serial No. 302,577.

To all whom it may concern:

Be it known that I, FREDERIC E. BERTRAND, a citizen of the United States, residing at Lynn, in the county of Essex and 5 State of Massachusetts, have invented certain new and useful Improvements in Sole-Channeling Machines; and I do hereby declare the following to be a full, clear, and exact description of the invention, such as 10 will enable others skilled in the art to which it appertains to make and use the same.

This invention relates to stock fitting machines and more particularly to such machines for channeling soles for use in the 15 manufacture of turn boots and shoes.

The prevailing style of shoe making at the present time demands the use of lasts having extremely pointed toes and this style is especially prevalent in turn shoes. To build 20 a shoe on these narrow toed lasts it is necessary to shape the sole with a much more pointed toe than has generally been in use, such soles being known to the trade as "peaked-toe" soles. Much difficulty has been 25 experienced in inseaming the shoes in which these soles are incorporated due to the fact that the operator of the inseaming machine is not permitted, by reason of the narrow 30 space at the extreme point of the toe, to sew down the advance side of the toe with stitches that are inserted, as they should be, at right angles to the line of feed. Consequently, in order to give more room for the 35 strokes of the awl and the needle the shoe is swung somewhat before it should be. As a result the stitches are distorted and the between substance weakened to such an extent that the shoe rips at the toe, frequently before its completion, causing a cripple. 40 This is particularly true in making turn shoes. In this type of shoe the step of turning it right side out places a severe strain on the inseam at the toe, which if it is not well made will rip.

45 The object of the present invention is to produce a sole which can be incorporated in shoes of the prevailing pointed toe style and securely fastened to the upper about the toe, thus avoiding the production of cripples 50 from the cause hereinbefore alluded to.

In accordance with this object a feature of the invention comprises the provision of means in a sole fitting machine which will

enable the operator to produce a stronger sewing-rib about the end of the toe where 55 the increased strain on the between-substance occurs. It is proposed to strengthen the sewing-rib by putting more material into the between-substance, *i. e.*, by making it 60 thicker. This increased thickness of between-substance will be employed only about the toe where the premature swinging of the sole, in order to make the quick turn required when inseaming pointed-toe shoes is 65 resorted to by the operative of the inseam- ing machine.

It is not customary in making turn soles, for the operative to increase the width of the margin, or feather, when cutting about the toe, as is done when making welt in- 70 soles. The position of the edge gage is, therefore, not changed in turn work, except when drawing on at the heel end for heel-seat sewed work, but in making peaked-toe soles the heel end is not channeled since the 75 shoes in which these soles are incorporated have nailed heel-seats. Accordingly, to im- prove the fitting of peaked-toe soles, the present inventor has conceived that a sim- 80 ultaneous movement of the edge gage and shoulder knife away from the point of the channel knife may be used to produce a thicker between-substance while at the same 85 time preserving the desired even width of the margin, or feather. Such a movement 90 will have the effect of throwing the chan- nel cut in, slightly, without altering the mar- ginal cut in any way. To this end the shoul- 95 der knife block is connected to the edge gage slide in such manner that while the knife may be adjusted vertically, as usual, for any edge thickness desired, it will also partake of any movement transverse to the line of feed which is given to the gage. With such a construction if the gage operat- 100 ing handle is moved in a direction to withdraw the gage, the shoulder knife is sim- 105 taneously withdrawn, but the relation of these two tools remains undisturbed and hence the even width of the margin is pre- served. The sole, however, is pushed across the line of feed beneath the channel knife in order to maintain edge contact with the gage and, as a result, more material is put into the between substance. In operating the 105 machine the edge gage operating handle will

be manipulated to throw the gage back when the shoulder knife is about one and one-half inches from the tip of the toe and then bring it forward again at a like point on the opposite side of the sole thus confining the thicker between-substance to the toe end of the sole alone.

To the accomplishment of this object and such others as may hereinafter appear, as will be readily understood by those skilled in the art, the invention comprises the features and combinations of parts hereinafter described and particularly pointed out in the appended claims.

15 The preferred embodiment of the invention is illustrated in the accompanying drawings, in which the invention has been shown for purposes of description as embodied in the turn work Goodyear universal channeling machine described by Letters Patent of the United States to the present inventor Nos. 1,030,704 and 1,030,710, both dated June 25, 1912.

20 In the drawings Figure 1 is a rear elevation of a portion of said channeling machine showing the operating tools and improved mounting of the shoulder knife; Fig. 2 is a plan of the parts shown in Fig. 1, including also the edge gage operating mechanism; 25 and Fig. 3 is an end elevation of a portion of the improved machine with the channel knife block removed.

25 In the illustrated embodiment of the invention the work support 10; the channel knife block 12 and channel knife 14, carried on the lower end of the channel slide 16; the shoulder knife block 18 and shoulder knife 20, carried on the lower end of the shoulder knife slide 22; the channel knife pressure gage 24 supported on the channel knife block; the shoulder knife pressure gage 26 at the lower end of the arm 28 depending from the independent slide 30; the edge gage 32 and its operating mechanism all may be, 30 and preferably are, the same as illustrated and described in said patents hereinbefore referred to, with the exception of the shape of the channel knife block 12 and its knife 14.

35 The channel knife block 12, it will be observed, is so formed as to support a channel knife 14 so shaped that in order to perform its function it must be positioned with its shank arranged vertically with respect to the plane of the work table instead of obliquely thereto as illustrated in said prior patents. The purpose of this shape of channel knife is more particularly for peaked-toe work, since it has been found that the obliquely arranged knife interferes with the 40 turning of the toe on soles of this style because of the small amount of room at the toe allowed by the rapidly converging sides of the sole. The vertical shank on the channel knife and the simplified holder therefor, 45 as will be recognized by those skilled in the

art, permit an easy turning of the peaked-toe soles without interference. This change forms no part of the present invention.

Also as in said prior patents, the slides 16, 22, and 30 are mounted in an oscillating carrier 33 which is actuated by a link 34 connecting it with a rocking arm 36 driven from an eccentric 38 on the driving shaft of the machine, and the work is fed across the work support 10 on the forward stroke of this carrier by means of the pressure of the gages 24 and 26 upon it. On the backward stroke of the carrier, however, the work is held from movement by pressure from the presser foot 40 carried at the lower end of a spring pressed carrier 41 which is given a vertical reciprocating movement by connections as described in said patents, with a second eccentric on the main shaft.

Two distinguishing features between the illustrated embodiment of the invention and the machine of said prior patents reside in the mounting of the shoulder knife block 18 upon its slide 22. The mounting is such as to permit a movement of the shoulder knife 20 across the line of feed relative to the point of the channel knife 14, without altering the depth or other characteristics of the cut which is made by either knife. It will be understood that when the knife is moved 95 in this manner, the operator moves the sole with it and to the same extent. As a result the between-substance is either increased or decreased in width according to the direction of movement of the knife and sole. A 100 convenient actuating mechanism for this movement of the shoulder knife is preferably connected to the edge gage operating mechanism in such manner that it partakes of the adjusting movement of the edge gage. 105

To accomplish this end the shoulder knife block must be so mounted upon its slide 22 as to permit of its having a movement horizontally across the end of this slide. Accordingly the slide 22 is provided at its 110 lower end with a block 42 of dovetail formation, the length of which is normal to the line of feed. Carried by the block 42 is a sliding way 46 having a lug 48 depending from its lower side, to which the shoulder 115 knife block 18 is secured in the usual manner by a bolt 50. The shoulder knife block in its construction and mounting is similar to the block of the present inventor's prior Letters Patent of the United States No. 120 1,030,703, dated June 25, 1912. Also depending from the lower side of the sliding way 46 is a rigid tubular member 52 which receives the vertical pin 54 connecting the edge gage support 56 with the oscillating 125 carrier 33, this connection being like and for the same purpose as the similar connection shown in said prior patents hereinbefore referred to. There is this difference, however, that the horizontal barrel 58 on the lower 130

end of the pin 54 is lengthened to completely fill the space between the two ears 60 supporting the pin 62 on which this barrel rotates, as the knife carrier 33 oscillates. The purpose of this construction is to insure that any movement across the line of feed imparted to the edge gage 32 by its adjusting mechanism will also impart a like movement to the pin 54 which is thus transmitted to the sliding way 46 and hence to the shoulder knife 20. An examination of said prior patents will disclose that heretofore the barrel 58 has been made shorter than the distance between the ears 60, thus permitting an adjustment of the edge gage relative to the shoulder knife. By the present arrangement, however, the edge gage and shoulder knife have a common movement across the line of feed and their relation to each other is never altered whatever position they may assume.

The edge gage support 56 is provided with a block 64 on its under side of dovetail formation which slides in a way, formed in a block 66, parallel to the slide way between the parts 42 and 46 carried by the frame, this construction being similar to that heretofore used. The edge gage support 56 is provided with a rack 68 at one end and meshing with this rack are the teeth on a segment 70 carried by one end of a lever 72 pivoted on the frame at 74. The lever 72 is connected to the mechanism within the barrel 76 and is oscillated to adjust the edge gage 32 across the line of feed by an operating handle 78. The mechanism between the operating handle 78 and lever 72 is all as illustrated in said prior Letters Patent and particularly described and claimed in Letters Patent of the United States to William C. Meyer, No. 984,773, dated February 21, 1911.

In operating the machine the sole is entered in the usual way with the operating handle 78 in such a position that the edge gage 32 is thrown to its forward position as shown in Fig. 2. This provides for the usual thickness of the between-substance between the channel and shoulder formed by the knives 14 and 20 respectively. When the feeding of the sole has progressed to a point about opposite one end of the tip line in the finished shoe, the operating handle 78 is moved in a direction to withdraw the edge gage to an extent determined by the setting of the adjusting stops provided for that purpose, and this movement, by reason of the connections described, carries the shoulder knife 20, with the gage, away from the point of the channel knife 14. Since the operator, during the fitting operation, always maintains the edge of the sole in contact with the edge gage, the effect of this movement is to increase the width of the between-substance, thereby adding to it the strength

which is desired for the sewing-rib at this portion of the sole. Those skilled in the art will understand that the character of neither of the cuts is changed by this operation. The feed is continued with the knives in this relative position until the sole has been swung at the toe and a point about opposite the other end of the tip line is reached, at which time the operating handle 78 is again moved, but in the reverse direction, so as to advance the edge gage 32 to its former position. The shoulder knife 20 is carried forward with the gage and the between-substance, from that point to the completion of the operation on the sole, is again reduced to its normal thickness.

Nothing herein contained is to be interpreted as limiting the invention in the scope of its application to use in connection with the particular machine, or the particular mode of operation, or both, selected for purposes of illustration and explanation. While the particulars of construction herein set forth are well suited to one mechanical form of the invention, it is not limited to these details of construction, nor is it to be understood that these particulars are essential since they may be variously modified within the skill of the artisan without departing from the true scope of the actual invention, characterizing features of which are set forth in the following claims by the intentional use of generic terms and expressions inclusive of various modifications.

What is claimed as new, is:—

1. A sole channeling machine having, in combination, a channel knife, a shoulder knife, and means for moving one of said knives across the line of feed toward and from the other without altering the depth of cut.

2. A sole channeling machine having, in combination, means for producing a marginal channel and an edge cut forming an intervening between-substance, and means operable while the machine is running for varying the thickness of said between-substance while preserving the original character of the cuts.

3. A sole channeling machine having, in combination, two knives for forming marginal cuts in the same face of the sole thus producing a between-substance, and means operable while the machine is running for varying the distance between the points of said knives without changing their vertical relation, to vary the thickness of the between-substance.

4. A sole channeling machine having, in combination, a work support, two knives opposite the work support for forming marginal cuts in the same face of the sole thus producing a between-substance and means operable while the machine is running for varying the distance between the points of

100

105

110

115

120

125

130

said knives by a relative movement thereof in a plane parallel to the supporting face of the work support.

5. A sole channeling machine having, in combination, a work support, a channel knife, a shoulder knife, and mechanism under control of the operator for moving one of said knives toward and from the other across the line of feed in a plane parallel 30 to the supporting face of the work support.

6. A sole channeling machine having, in combination, a channel knife, a shoulder knife, an edge gage, edge gage operating mechanism, and means controlled by said 35 mechanism for moving the shoulder knife bodily toward and from the point of the channel knife.

7. A sole channeling machine having, in combination, an edge gage support carrying 40 20 an edge gage, a knife block carrying a shoulder knife, and means for moving said gage and knife across the line of feed without altering their relation to each other.

8. A sole channeling machine having, in combination, an edge gage support carrying 45 25 an edge gage, a knife block carrying a shoulder knife, connections between said support and block to insure a common move-

ment thereof across the line of feed, and suitable actuating means.

30

9. A sole channeling machine having, in combination, an edge gage, means for adjusting said gage across the line of feed, an edge knife, and connecting mechanism between said tools whereby the edge knife partakes of the movements of the edge gage.

35

10. A sole channeling machine having, in combination, a knife slide, a knife block supported by said slide, a sliding connection between said slide and block permitting 40 movement of the knife across the line of feed, and actuating means for moving said block relatively to said slide while the machine continues in operation.

40

11. In a sole channeling machine, means 45 for supporting and feeding the sole, means for forming a between-substance, and means for varying its thickness during the operation of the machine.

12. In a sole channeling machine, means 50 for supporting and feeding the sole, means for forming a between-substance, and means under control of the operator for varying its thickness on any desired portion of the sole fed to the forming means.

FREDERIC E. BERTRAND.
